United States Patent Office

Des. 210,070
Patented Feb. 6, 1968

210,070

CAMPER

Sidney P. Pair, 1511 Oliver St., and Jerry W. Pair, 1307
Oliver St., both of Weatherford, Tex. 76086, and R.
W. Beck, Jr., 2123 NW. 23rd St., Fort Worth, Tex.
76106

Filed Aug. 26, 1966, Ser. No. 3,604

Term of patent 14 years

(Cl. D14—3)

Fig. 1

Fig. 2

Fig. 3

FIG. 1 is a side elevational view of a camper embodying our new design;

FIG. 2 is a front elevational view thereof; and

FIG. 3 is a rear elevational view thereof.

The side opposite to that shown in FIG. 1 is a mirror image thereof.

The dotted line showings in the drawing are for illustrative purposes only.

We claim:

The ornamental design for a camper, as shown and described.
